ABSTRACT OF THE DISCLOSURE

Setter and method for keeping flat tile straight and
free of soiling during firing of glaze by supporting tile
on cantilever supported opposed sets of shelves whose
outer edges provide parallel horizontal bearing surfaces
so that a tendency of unsupported tiles to sag in the
center during fire is counterbalanced by overhanging
margins of the tiles. Under surfaces of shelves are sloped
so that accumulations of volatilized glaze not ventilated
away or carried out by condensation on undersides of
tiles stacked in the setter will run to the sides and not
drop on tiles. Edges of shelves are but slightly raised
above upper shelf surfaces which thus act as limits for
the sagging of the tile margins during fire.

This invention relates to improvements in kiln furniture
for the firing of the tile and, more particularly, to setters
for the firing of glazed flat ceramic tiles for walls, floor-
ing, or the like.

At the stage of manufacture of ceramic tiles at which
setters made according to this invention are employed,
the tile is usually in the condition of green ware com-
prising a body of dry unfired clay of relatively thin
cross-section and conventional polygonal shape (usually
square or otherwise rectangular). The relatively
smoother upper surface of the clay body carries a dried
coating of frit in which are the necessary fluxes, opacifiers,
and colors to be fused into an adherent surface glaze
when the clay body is fired to the semi-vitreous condi-
tion of the manufactured tile.

With the green tile prepared for firing as described
above, it has heretofore been the preferred practice in
the art to support the tile in shallow setter trays of a
suitable refractory material. These trays have flat, imper-
forate bottoms and sides extending above the tile-support-
ing surface of the bottom a distance sufficient to provide
clearance between the glazed surface of a tile placed in
one tray and the underside of a tray above it. With one
or more tiles (depending upon the size of the tiles and
trays) placed in each tray, a number of trays are stacked
into a bung with a cover plate over the top tray of the
bung. The trays making up a bung are usually cemented
together at the parting line between the sides of one
tray and the bottom of the tray above to prevent the
shifting of the trays with respect to each other as the
bungs are loaded on the cars on which the bungs are
conveyed in and out of the kiln for firing. The sides
of the trays are provided with openings to permit the
movement of gases in and out of the trays, but the size
of the openings must be relatively limited to provide the
necessary strength for supporting other trays in the
bung as well as the bungs which may be loaded on top
of the bottom bungs when loading a kiln car. The func-
tion of the flat bottom of the trays in a bung is to provide
a flat supporting surface upon which each tile will rest
so that the tile will not warp as it is brought to its

2

maximum firing temperature; also, the bottom of one
tray (plus the cover plate in a bung) serves to shield
from dirt and contamination the molten glaze which
fuses together and to the body of the tile as it is being
fired. After the tile is fired and the bungs cooled, the
trays are removed, broken apart to remove the tile,
and then reused.

A problem of the above-described tray-style of setter
is that in repeated usage, the trays themselves tend to
warp so that the trays will not support and produce
straight tile, in which case, they must be discarded.
The tray setters are also subject to considerable cracking
and breakage in the stacking, breaking apart, and other
handling of the trays making up the bungs. Still another
fault of the above-described tray setters is that, in re-
peated re-use, glaze will volatilize and condense on the
underside of the tray above it. In time, this volatilized
glaze may accumulate to the point where, at the maxi-
mum firing temperature, it drops onto the tile below it
or, in reaching this temperature and because the rate
of thermal expansion of the glaze is different from that
of the refractory from which the trays are made, the
accumulated glaze spalls off the underside of the tray
and falls onto the glaze of the tile beneath; in either
case, the tile is spoiled and must be discarded. Also, a
considerable amount of labor is involved in cementing
up the bungs and, because the so cemented bungs are
seldom of precisely equal height, time-consuming care
must be used in loading layers of bungs upon another
to provide a stable load in the kiln cars.

In addition to the above faults and expenses of the
system of firing tile in setter trays which have heretofore
been considered inherent and unavoidable, a less ap-
preciated but nonetheless serious element of cost is that
the trays themselves are more massive than the mass
of the tile being produced in order to provide the required
strength and stability of the bungs. As a consequence,
a major portion of the heat produced in a tile kiln, as
well as its volumetric capacity is taken up by the setters,
rather than by the tiles to be fired.

It is the object of this invention to provide a setter
for firing tile which not only produces straight tile but
eliminates many of the above faults and disadvantages
of the tray setters as above described. That is, the cost,
weight, and mass of refractory material per tile being
fired are greatly reduced and the capacity of a kiln greatly
increased, both volumetrically in that a greater number
of tiles may be carried by a kiln car (and in the rate of
production in that the tiles may be fired faster because
less time is required to bring a lesser mass of refractory
material up to temperature). Also, the labor involved
in cementing the trays into a bung is eliminated and the
care and time required in loading the kiln cars or other
conveyor means is minimized.

A still further advantage is that, due to improvement
of ventilation of the tiles as fired, more uniform color
can be developed among the tiles of a lot being fired
and a better color match may be obtained between tiles
fired in different lots. And, due to the configuration of
the tile supports, the spoilage of glaze from accumulations
of volatilized glaze on the setter is substantially eliminated.

Other and further objects and advantages of this inven-
tion will be apparent from the following specification,
claims, and drawings, in which:

FIG. 1 is a front elevational view of a two-cell tile
setter made according to this invention.

FIG. 2 is a fragmentary side elevation of the setter
shown in FIG. 1, showing in phantom the location of a
tile supported on the uppermost of an opposed pair of
cantilever shelves.

FIG. 3 is a detailed elevation taken from FIG. 1 and showing in phantom the location and support of tiles on the cantilevers.

As shown in FIGS. 1 and 2, a tile setter 10 made according to this invention comprises a box having a pair of side walls 11 supporting a bottom 12 and top 13, leaving an open front and back. To minimize the mass of the refractory material making up the setter 10 without appreciably reducing the strength and stiffness of them, the side walls 11 are provided with suitable vertically extending recesses 14 and the bottom 12 and the top 13 are provided with horizontally extending recesses 15 and 16, respectively. Depending upon the size of the tile to be fired, the modular dimensions of the setter with respect to the dimensions of the kiln car or conveyor on which it is to be placed, and the weight of the setter, when loaded with tile, that is convenient to handle, the top, bottom, and sides of the setter may define a single open-ended cell or a plurality of cells. In this particular embodiment shown, the setter is divided into two cells by a vertical partition 17.

In each cell the sides thereof are provided with a plurality of opposed horizontal cantilever shelves 18 extending inwardly toward each other and slightly upwardly from the side walls with which they are integral. Referring to FIG 3, the side wall 10 and partition 17 are spaced from each other a horizontal distance sufficient to permit a green tile, with the unfired glaze uppermost, to be inserted into the cell with sufficient clearance to permit easy loading and unloading of a tile onto the opposed shelves. Each shelf 18 extends into the cell a distance sufficient to locate its outer and uppermost edge in a position to support a tile along a line midway between the center and the adjacent edge of the tile. It is to be noted that each shelf is slightly thicker at its root where it is integral with a side wall or partition than it is at its outer end, and that the angle (a) at which the underside of a shelf extends with respect to its supporting wall is slightly greater than the angle (b) at which the upper surface extends. This is to provide structural strength with a minimum of mass of refractory while presenting the upper edge of the shelf as a line of support. It is also to be noted that the opposed pair of shelves are spaced from each other a distance to provide a spacing between tiles supported thereon at least twice the thickness of the tiles.

The bottom 10 is provided with horizontal ridges 19 which afford tile-supporting lines parallel to and vertically aligned with the lines of support provided by the outer upper edges of the shelves 18. The bearing surfaces of the top and bottom as defined by the recesses 15 and 16 are preferably parallel and provide an over-all height equal to the height of other setters to be loaded as a layer on a kiln car.

With the setter loaded with tiles as indicated in FIG. 3, it is placed with similar setters on a kiln car or conveyor and the tiles are then fired. In essence, the operation and advantage of this invention flow from a utilization of the discovery that, contrary to prior practice with tray setters and the like, it is not necessary to support a tile having a typical clay body and thickness during its fire throughout the entire undersurface or substantially so. Rather, the tile will remain straight if it is simply supported along a line approximately midway between its edge and center so that the weight of the portion of tile which overhangs one side of the line of support will approximately balance the weight of the portion which overhangs the other side of the line of support, as shown in FIG. 3.

By the above construction, a substantial portion of the mass of refractory material heretofore taken up by the bottom of tray setters is eliminated and a setter made according to this invention is equivalent to a bung of tray setters, but of substantially less height than a bung carrying an equal number of tiles. At the same time, the glaze on the tiles is shielded by the tile above it, rather than by

the bottom of a superimposed tray in a bung of tray setters. There is less build-up of volatilized glaze to cause spoilage by dropping or spoiling because much of the glaze volatilized from the surface of one tile will deposit on the underside of the shielding tile above it and, thereby, be removed when the tiles are fired and removed from the setter. Also, due to the greater ventilation permitted by the open ends of the setter, much volatilized glaze that might accumulate in conventional setters may be exhausted out of the setters by the flow of gases through the setters. Another advantage of the greater ventilation is that the glaze is brought to fusion and colors are oxidized more evenly throughout the mass of tile being fired, producing more uniform color between tiles of a lot being fired and permitting a better duplication of conditions so that the colors of different lots can be more evenly matched.

It is also apparent from this construction that no labor is lost in cementing setter trays together and, because all setters may be of equal height, one layer of setters in a kiln car will provide a level, stable surface for a succeeding layer, enabling cars to be loaded more quickly.

This invention is not to be considered limited to the specific illustrative embodiment disclosed but may be modified to meet the requirements of specific tiles, kilns, and loading techniques and requirements. Accordingly, those skilled in the art may vary this invention within the scope of the appended claims without departing from the spirit and purpose thereof.

30 What is claimed is:

1. A tile setter for firing ceramic tile comprised of opposed side walls joined at their top and bottom to define a cell, a plurality of cantilever shelves carried by each side wall, said shelves being inclined upwardly with respect to the wall supporting them, and shelves carried by said opposite walls being arranged in pairs to provide pairs of tile supporting edges, the two edges in any one pair being equidistant from the bottoms of the supporting walls and one edge in such pair being spaced from its supporting side wall a distance equal to the distance the other edge in the pair is spaced from its supporting side wall, whereby, when a tile is supported on a pair of said edges, the weight of tile between said edges is substantially counter-balanced by the weight of the portion of said tile extending beyond said edges toward the supporting side walls.

2. A tile setter as defined in claim 1 in which said side walls are spaced from each other a distance to provide clearance for a tile to be supported on the said pairs of shelves and the shelves of said pairs extend toward each other to support said tile on their respective tile-supporting edges providing lines of support located substantially midway between the center of a tile and the edges of said tile adjacent said walls.

3. A tile setter as defined in claim 2 including a bottom member joining adjacent side walls, and a pair of ridges on said bottom member spaced from each other and the side walls as the supporting edges of a pair of shelves are spaced from each other and the side walls.

4. A tile setter as defined in claim 2 which is open at the front and back to permit ventilation of said cell and insertion of tiles into said cell for support on the tile-supporting edges of pairs of said shelves.

5. A tile setter comprising a plurality of cells as defined in claim 1 and joined together by means of a common side wall between cells.

6. A multi-cell tile setter comprising a top member, a bottom member, side walls, and at least one vertical partition forming a cell, as defined in claim 1, between said partition and said side wall.

7. The method of firing flat green tile to minimize sagging during fire comprising the steps of providing a refractory setter with opposed vertical side walls and at least one open side, said side walls being spaced internally from each other a distance greater than the width of the

tile to be fired therein, each of said side walls carrying an internal shelf extending toward an internal shelf carried by the opposed side wall to provide a pair of adjacent substantially parallel and horizontal shelf edges functioning as narrow bearing surfaces for a tile to be fired thereon and said edges being above the upper horizontal surface of their respective shelves and spaced apart a distance equal to substantially one-half the width of tile to be fired in said setter, placing a green flat tile on said edges so that substantially equal margins are supported above each of the shelves in the pair and firing said assembled setter and tile, maintaining said shelf edges substantially horizontal during firing so that the margins of said tile substantially counterbalance the center portions supported between said edges.

8. The method as defined in claim 7 including, in the step of providing a setter as defined therein, providing a setter with a plurality of sets of said shelves, the said edges of which are spaced vertically with respect to each other a distance at least twice the thickness of said tiles and in which tiles placed on said shelves are coated on their upper surface with unfired glaze but are substantially free of glaze on their undersurfaces, whereby the underside of a tile stacked in spaced arrangement on a set of said shelves and supported between said edges above another tile serves as a receptor of at least some of the glaze volatilized during the step of firing.

9. The method as defined in claim 8, including in the step of providing a setter as defined therein, a setter in which the undersurfaces of said shelves slope upwardly toward its inner edge from a point on its supporting wall sufficient to provide clearance from a tile supported beneath said shelves, whereby glaze which volatilizes from said tiles during firing and condenses on the undersides

of said shelves will tend to run toward said walls rather than drop on a tile beneath.

10. The method as defined in claim 9, including, in the step of providing a setter as defined therein, providing a setter in which the upper surface of said shelves, in their areas intended to be overhung by said tiles, are at no point vertically above their respective edges but are closely adjacent the planes defined by the respective opposed and parallel horizontal edges, whereby the upper surfaces of said shelves serve as limits for the sagging of the margins of said tiles during the step of firing.

11. The method as defined in claim 10, including, in the step of providing a setter therein, providing a setter with opposed open sides, and ventilating through said open sides during the step of firing.
